TUBE-SHELL HEAT EXCHANGER

William H. Poore, Livonia, Mich., assignor to American Radiator & Standard Sanitary Corporation, New York, N.Y., a corporation of Delaware

Filed June 21, 1965, Ser. No. 465,374

9 Claims. (Cl. 165—178)

This invention relates to tube-shell heat exchangers, and particularly heat exchangers employing flexible tubes within the shell.

Recently heat exchangers employing flexible tubes of plastic material have been proposed for the cooling or heating of fluids which would corrode copper or other metal heat exchange tubes. The plastic tubes are flexible and limp like spaghetti. Hence there is a problem in installing the tubes in the shell, and supporting them after installation.

A primary object of the present invention is to provide a tube-shell heat exchanger wherein flexible tubes can be readily installed in the shell and supported adequately after their installation.

Another object is to provide a tube-shell heat exchanger wherein the mechanism for supporting the flexible tubes is comprised of a relatively small number of parts.

Other objects of this invention will appear from the following description, accompanying drawing, and appended claims.

In the drawing:

The single figure is a longitudinal sectional view taken through a tube-shell heat exchanger constructed according to the invention.

Before explaining the present invention in detail, it is to be understood that the invention is not limited in its application to the details of construction and arrangement of parts illustrated in the accompanying drawing, since the invention is capable of other embodiments and of being practiced or carried out in various ways. Also, it is to be understood that the phraseology or terminology employed herein is for the purpose of description and not of limitation.

In the drawing there is shown a tube-shell heat exchanger comprising a rigid cylindrical metal shell 10 having a fluid inlet 12 and fluid outlet 13. The upper end of the shell is flanged at 15 to receive the plastic tube sheet 16 which supports and has mounted therein a large number of flexible plastic tubes 18. Positioned against the upper end face of tube sheet 16 is the flange 19 of a bonnet or header which is equipped with an inlet 22 for directing fluid into the tubes 18.

The lower ends of tubes 18 extend through and are anchored in a floating plastic tube sheet 23 which includes a relatively large diameter cylindrical section 25, a slightly smaller diameter cylindrical section 26 and an intermediate reduced-diameter section which forms a groove 28. In the assembled condition of the heat exchanger, section 25 of the lower tube sheet has its periphery sealingly engaged with a compressed O-ring seal 30 which is positioned in a groove in the flange 32 of shell 10. The periphery of section 26 sealingly engages a compressed O-ring seal 33 which is positioned in a groove in a flange 35 of a bonnet or header 36. Interposed between flanges 32 and 35 is a split ring 38 comprised of two semi-annular ring shaped discs, suitable bolts 50 being trained through openings in the flanges and interposed discs 38 to secure the components in their illustrated positions. It will be seen that fluid introduced into inlet 22 flows through the tubes 18 into the header 36 and out through outlet 52. The shell fluid introduced through inlet 12 flows around the outer surfaces of tubes 18 and out through outlet 13. Split ring 38 constitutes a detent means to retain tube sheet 23 in its shown position.

2

In the illustrated heat exchanger, tubes 18 and tube sheets 16 and 23 are formed of plastic material, the ends of the tubes being bunched together and inserted into a central opening in each tube sheet for securement therein by a process not part of the present invention. For purposes of this invention the tubes could be formed of various flexible materials such as elastomers, fabric, helical metal coils, or various different plastics. Whatever the tube material and method of securing the tubes to the tube sheets, the tubes are very flexible and limp and offer no support, especially in an axial direction, unless adequately supported in the shell. For manufacturing reasons the tubes are preferably permanently secured to the tube sheets before insertion of the tube-tube sheet assembly into the shell.

The construction of the tubes and tube sheets makes it difficult to install and adequately support the tube-tube sheet assembly in the heat exchanger shell. However, by grooving and dimensioning the lower tube sheet 23 as shown in the drawing, it is possible to readily install the tube-tube sheet assembly into the shell in a single operation.

Thus, with bonnets 20 and 36 dissociated from shell 10 and the shell in an upright position, the tube-tube sheet assembly can be lowered or dropped into the shell and the peripheral surface of tube sheet 23 allowed to slide downwardly along the inner surface 55 of cylindrical shell 10.

It will be noted that section 26 of the tube sheet has a smaller diameter than section 25; this allows section 26 to pass freely through pre-placed O-ring 30 without being restrained. Section 26 can thus take a position slightly below the lower edge of shell 10, after which the tube sheet can be manually pulled down to cause section 25 to be gripped by O-ring 30 with sufficient friction to form the desired seal. When tube sheet 23 is in its illustrated position the two separated parts of split ring 38 can be installed on the lower face of flange 32 and moved radially inwardly into groove 28. Then bonnet 36 can be installed, and bolts 50 utilized to secure the parts in their illustrated positions. Suitable bolts 56 can be utilized to secure bonnet 20 against the upper face of tube sheet 16. During installation of bonnet 36 (with pre-positioned O-ring 33 therein) split ring 38 may act as an abutment to prevent excessive upward displacement of the tube sheet.

Tube sheet section 26 has a diameter which is sufficiently less than the uncompressed inner diameter of O-ring 30 as will enable the tube sheet to fall to its illustrated position during installation of the tube bundle. O-ring 33 is however made with an inner diameter of sufficiently small dimension as to provide an interference fit with the surface of tube sheet section 26 when header 36 is pushed upwardly against split ring 38. Within the broader aspects of the invention the groove 29 and ring 38 relationship could be replaced with differently configured structures, as for example radial holes in the intermediate peripheral surface of sheet 23 and cooperating set screws or pins carried by shell 10.

The heat exchanger can be formed to different sizes, but as an example the shell can be on the order of one to ten feet in length and the tube bundle can have a diameter on the order of two to twelve inches. These dimensions would make installation of the tube-tube sheet assembly quite difficult except for the special construction of the lower tube sheet.

Groove 28 is preferably made slightly wider than the axial thickness of split ring 38 to compensate for manufacturing variations in parts dimensions, as for example the length of shell 10. If the heat exchanger is used in a horizontal prone position, the weight of spaghetti-like tubes 18 will tend to draw tube sheet 23 toward tube sheet 16. However shoulder 29 formed by groove 28 will hold the

tube sheet 23 in a stationary position. In service seal 30 seals shell space 57 from the ambient, and seal 33 seals space 59 from the ambient; the two seals collectively seal spaces 57 and 59 from one another.

It will be understood that the drawing and description are merely illustrative of the principles of the invention, and that variations in structure and dimension may be resorted to without departing from the spirit of the invention as set forth in the appended claims.

What is claimed is:

1. A heat exchanger comprising a shell; flexible fluid tubes extending within the shell; means floatably supporting the tubes adjacent one end of the shell; a header located at said one end of the shell and operable to admit fluid to or withdraw fluid from the tubes; detent means rigid with the header and shell for limiting axial movement of the floating tube support means; first seal means located between the shell and tube support means for sealing the shell space from atmosphere; and second seal means located between the header and tube support means for sealing the header space from atmosphere.

2. The heat exchanger of claim 1 wherein the tube support means comprises an axially thickened tube sheet having a groove in its peripheral surface, and said limiting means comprises detent mechanism projecting into the groove; the groove having a greater axial dimension than the detent mechanism, whereby the tube sheet is free for limited axial movement in either direction.

3. A heat exchanger comprising a shell; flexible fluid tubes extending within the shell; a tube sheet floatably positioned within one end of the shell and having the tubes secured thereto; said tube sheet having a groove in its outer periphery; a header located at said one end of the shell and operable to admit fluid to or withdraw fluid from the tube; tube sheet retainer means clamped between the shell and header, and projecting into the aforementioned groove to limit axial movement of the tube sheet; first seal means mounted in the shell and engaging the peripheral surface of the tube sheet to seal the shell space from atmosphere; and second seal means mounted in the header and engaging the peripheral surface of the tube sheet to seal the header space from atmosphere.

4. A heat exchanger comprising a shell; flexible fluid tubes extending within the shell; an axially elongated tube sheet floatably positioned within one end of the shell and having the tubes secured thereto; said tube sheet having a first groove in its outer periphery; a header located at said one end of the shell and operable to admit fluid to or withdraw fluid from the tubes; apertured flanges formed on the shell and header; apertured sheet retainer means sandwiched between the shell flange and header flange, and projecting into the aforementioned groove to limit axial movement of the tube sheet; connectors extending through the apertures to secure the retainer means, shell and header together; a second groove in a surface of the shell facing the periphery of the tube sheet; an O-ring positioned in said second groove to seal the shell space from the atmosphere; a third groove in a surface of the header facing the periphery of the tube sheet; and a second O-ring positioned in the third groove to seal the header space from the atmosphere.

5. A heat exchanger comprising an elongated shell; a first tube sheet engaging an end surface of the shell; flexible fluid tubes permanently anchored to said tube sheet and extending within the shell; a second tube sheet permanently anchored to the tubes and engaging an inner surface of the shell; said second tube sheet having a groove in its periphery; retainer means abutting the other end surface of the shell and extending into the groove; a fluid header means abutting the retainer means and having an inner surface thereof engaging the periphery of the second tube sheet; the peripheral outline of the second tube

sheet being no larger than the inner cross sectional dimension of the shell whereby the tube-tube sheet assembly is installable in and removable from the shell by movement through the portion of the shell which defines the first mentioned end surface; first seal means interposed between the second tube sheet and shell, and second seal means interposed between the fluid header means and second tube sheet.

6. A heat exchanger comprising an elongated shell; a first tube sheet secured to one end of the shell; flexible fluid tubes extending from said tube sheet within the shell; a second tube sheet carried by the ends of the tubes remote from the first tube sheet; said second tube sheet comprising a first relatively large diameter section conforming to the internal diameter of the shell, and a second section of smaller diameter than the first section; said second tube sheet being positioned with its first section disposed within the shell and its second section beyond the shell; a first seal carried by the shell and having an interference fit with the first section of the second tube sheet to prevent fluid flow therewith; header means located beyond an end of the shell and having an internal surface surrounding the periphery of the second section of the second tube sheet; and a second seal carried by the header means and having an interference fit with the second section of the second tube sheet to prevent fluid flow therewith.

7. The heat exchanger of claim 6 and further comprising detent means operable to prevent axial movement of the second tube sheet.

8. A heat exchanger comprising an elongated shell; a first tube sheet secured to one end of the shell; flexible fluid tubes extending from said tube sheet within the shell; a second tube sheet carried by the ends of the tubes remote from the first tube sheet; said second tube sheet comprising a first relatively large diameter section conforming to the internal diameter of the shell, and a second section of smaller diameter than the first section; said second tube sheet being positioned with its first section disposed within the shell and its second section beyond the shell; a first seal carried by the shell and having an interference fit with the first section of the second tube sheet to prevent fluid flow therewith; header means located beyond an end of the shell and having an internal surface surrounding the periphery of the second section of the second tube sheet; and a second seal carried by the header means and having an interference fit with the second section of the second tube sheet to prevent fluid flow therewith; the outer diameter of the second section of the second tube sheet being sufficiently less than the inner diameter of the first seal as to permit said second section to pass through the first seal without frictional interference between the seal and second section.

9. The heat exchanger of claim 8 wherein the second tube sheet is formed with a peripheral groove between its first and second sections; the heat exchanger further comprising detent means rigid with the shell and projecting into the groove to prevent substantial axial movement of the second tube sheet.
